(57) **CLAIM**

The ornamental design for a speakerphone, as shown and described.

DESCRIPTION

FIG. 1 is a perspective view of a speakerphone, showing a first embodiment of our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a perspective view of a speakerphone, showing a second embodiment of our new design;

FIG. 9 is a top plan view thereof;

FIG. 10 is a front elevational view thereof;

FIG. 11 is a rear elevational view thereof;

wherein a left side elevational view thereof is identical to FIG. 5;

wherein a right side elevational view thereof is identical to FIG. 6;

FIG. 12 is a bottom plan view thereof;

FIG. 13 is a perspective view of a speakerphone, showing a third embodiment of our new design;

FIG. 14 is a top plan view thereof;

FIG. 15 is a front elevational view thereof;

wherein a rear elevational view thereof is identical to FIG. 4;

FIG. 16 is a left side elevational view thereof;

FIG. 17 is a right side elevational view thereof;

wherein a bottom plan view thereof is identical to FIG. 7;

FIG. 18 is a perspective view of a speakerphone, showing a fourth embodiment of our new design;

FIG. 19 is a top plan view thereof; and,

FIG. 20 is a front elevational view thereof; wherein a rear elevational view thereof is identical to FIG. 11;

wherein a left side elevational view thereof is identical to FIG. 16;

wherein a right side elevational view thereof is identical to FIG. 17;

wherein a bottom plan view thereof is identical to FIG. 12.

The evenly dashed lines shown in the drawings depict portions of the speakerphone that form no part of the claimed design. The dash-dot lines shown in the drawings

(Continued)

show a symbolic break in length. Any portions of the article between the dash-dot lines form no part of the claimed design.
